BLOOD LANCET

Teruo Endoh, Seki City, Japan, assignor to
Feather Kogyo Kabushiki Kaisha

Filed July 31, 1972, Ser. No. 276,679

Term of patent 14 years

Int. Cl. D24—02

U.S. Cl. D83—12 R

FIG. 1 FIG. 2 FIG. 5

FIG. 3 FIG. 4

FIG. 1 is a front elevation of a blood lancet showing my new design.

FIG. 2 is a rear elevation thereof.

FIG. 3 is a top plan view thereof.

FIG. 4 is a bottom plan view thereof.

FIG. 5 is a side elevation thereof.

FIG. 6 is a top perspective view thereof; and

FIG. 7 is a cross section taken on line 7-7 of FIG. 6.

I claim:

The ornamental design for a blood lancet, as shown.
